JOE FIELDS _____ INVENTOR.

BY
Rich and B. Oliver _____ ATTORNEY.

UNITED STATES PATENT OFFICE.

JOE FIELDS, OF CLENDENIN, WEST VIRGINIA.

PIPE WRENCH.

Application filed August 26, 1921. Serial No. 495,712.

To all whom it may concern:

Be it known that I, JOE FIELDS, a citizen of the United States, residing at Clendenin, in the county of Kanawha and State of 5 West Virginia, have invented certain new and useful Improvements in Pipe Wrenches, of which the following is a specification.

This invention relates to pipe wrenches and more particularly to a novel improved 10 tool wherein the adjustable jaw may be released and moved to different positions with facility and ease.

A primary object of the invention is to produce a pipe wrench having the usual 15 type of operating handle provided with a pivoted, spring retained sleeve thereon for receiving the shank portions of an adjustable jaw whereby said jaw may be released from engagement with the handle by rocking said sleeve on its pivot.

A still further object of the invention is to produce a pipe wrench of the class above set forth wherein a movable jaw receiving sleeve is adapted to carry a replaceable 25 guide or stationary jaw including a guide in the form of a yoke secured to the handle of the wrench for the shank of the adjustable jaw, said guide also being adapted to secure the ends of a spring cooperating with 30 the movable sleeve whereby the same is maintained in a locked position with the handle.

Another and very important object of the invention is the provision of a pipe wrench 35 of the class above set forth wherein the parts are extremely simple in construction, easily assembled, rigid and durable, highly efficient in operation, practical and capable of being manufactured at a very low cost 40 whereby its commercial possibilities are greatly enhanced.

The invention will be best understood from a consideration of the following detailed description taken in connection with 45 the accompanying drawing forming a part of this specification, with the understanding, however, that the invention is not confined to any strict conformity with the showing in the drawing, but may be changed 50 and modified so long as such changes and modifications mark no material departure from the salient features of the invention expressed in the subject matter being claimed.

I attain the above objects and others in 55 the accompanying drawings, wherein:

Figure 1 is a side view partly in section; and

Fig. 2 is a front view of the wrench.

Referring now to the drawing wherein 60 like reference characters designate corresponding parts throughout the several views, 5 designates the handle and 6 the inwardly curved top thereof which is provided with teeth 7 on its front face for engagement with the teeth 8 on the body or shank portion 9 of an adjustable jaw 10. Pivoted to the top or curved portion of the handle 5 I have provided a sleeve 11, the same being adapted to oscillate or rock on 65 the pivot 12 whereby the shank of the movable jaw 10 may be disengaged from the teeth of the curved portion 6 of said handle so that the said adjustable jaw may be regulated to suit the needs and as occasion may 70 require.

Welded or otherwise secured to the handle 5 and below the pivotal connection of the sleeve, I have provided a yoke designated in its entirety by the numeral 12 80 which forms a guide for the lower end 13 of the adjustable jaw 10, a stop or pin 14 being provided in said bottom 13 of the jaw whereby the same is prevented from being entirely withdrawn and removed from the 85 guide. The front ends of the yoke 12 are provided with hooked extensions 16 which receive the ends 16 of a resilient spring 17, said spring being suitably secured to the rear portion 18 of the sleeve so 90 as to maintain the adjustable jaw 10 in engagement with the handle as above referred to.

The sleeve 11 is also formed with a tongue 95 19 which is adapted to receive a replaceable stationary die or jaw 20, which of course cooperates with the movable jaw when engaging a part.

By reason of this construction, it can be readily seen that by simply rocking the 100 sleeve 11 on its pivot 12 that the movable jaw 10 may be disengaged from the curved handle portion 6 so that the said movable jaw may be adjusted to the desired position to engage a part. The yoke 12 performs of 105 course the double function of acting in the nature of a guide for the end of the shank 13 of the movable jaw as well as forming

a securing means for the ends of the spring 17 which maintains the sleeve in engaged position with its shank 9 to the handle.

In the accompanying drawings, I have 5 illustrated my invention embodied in one form by way of example, and which in practice has been found to be highly satisfactory in obtaining the desired results. It will be obvious however, that other embodiments 10 may be adopted, and that various changes in the details of construction may be resorted to by those skilled in the art without departing from the spirit and scope of the invention. It is furthermore understood 15 that the invention is not necessarily limited or restricted to the precise elements shown except in so far as such limitations are specified in the subject matter being claimed.

Having shown and described my invention 20 what I now claim as new and desire to secure by Letters Patent of the United States is:—

1. A wrench comprising a handle having a curved top provided with teeth formed on 25 its inner face, a sleeve pivoted to the handle adjacent to the top, a stationary jaw connected with the sleeve, a sliding jaw including a laterally extending jaw face and a shank, the shank being slidably mounted in 30 the sleeve and having rack teeth formed on one edge thereof for engaging the teeth on said handle, a yoke secured to the handle inwardly of the sleeve and projecting laterally from said handle when slidably receiving 35 said shank, a leaf spring secured to the yoke and engaging the sleeve for maintaining the shank of the sliding jaw in en-

gagement with the teeth on the handle, and a pin carried by the shank for engaging said yoke to limit the outward movement the 40 sliding jaw.

2. A wrench comprising a handle having a curved top provided with teeth on its inner face, a sleeve pivoted to the handle adjacent its top, a slidable jaw carried by said 45 sleeve and having teeth on its shank for engagement with the curved top of the handle, a yoke secured to the handle constituting a guide and a stop for the shank of said slid- 50 able jaw, and a resilient element fastened to the yoke for maintaining the adjustable jaw in engagement with the curved portion of the handle.

3. A wrench comprising a handle having a curved top provided with teeth formed on 55 its inner face, a sleeve pivoted to the handle adjacent the top and provided with a tongue for receiving a replaceable stationary jaw, a slidable jaw carried by said sleeve and adapted to engage the curved top portion of the handle, a yoke secured to the handle and provided with hooked extensions, 60 said yoke constituting a guide and a stop member for the shank of the slidable jaw, and a spring engaging the sleeve and connected to the hooked extensions for maintaining the slidable jaw in engaged position with the handle. 65

In testimony whereof I affix my signature in presence of two witnesses.

JOE FIELDS.
